C. R. DE LAUBENFELS

WEATHER STRIP

Filed March 28, 1928

UNITED STATES PATENT OFFICE.

CLARENCE R. DE LAUBENFELS, OF LOS ANGELES, CALIFORNIA.

WEATHER STRIP.

Application filed March 28, 1928. Serial No. 265,253.

This invention relates to improvements in weatherstrips, and more especially to weather strips adapted to be used in connection with swinging closures such as casement windows, doors, and the like.

An object of the invention is to provide an improved weatherstrip adapted to form a novel and simple weatherproof joint between a closure and the associated casement therefor when the closure is swung to closing position.

A further object of the invention is the provision of a weatherstrip of the character described, especially adapted for use upon the lower rail or sill of a casement to establish a tight seal between it and the bottom of the associated closure.

A further object is the provision of a weatherstrip of the character described, which is of exceedingly simple construction, which is capable of being very easily and economically manufactured, which can be very easily and quickly installed, and which is capable of efficiently performing the services required of it.

With the foregoing and other objects in view which will be made manifest in the following detailed description and specifically pointed out in the appended claims, reference is had to the accompanying drawings for an illustrative embodiment of the invention, wherein:

Figure 1 is a perspective view of a casement with a casement window hinged therein and showing one of the weatherstrips of the present invention mounted upon the sill to establish a weather-proof joint between the sill and the window.

Fig. 2 is a fragmentary, transverse, sectional view taken upon the line 2—2 of Fig. 1.

Fig. 3 is a view similar to Fig. 2, showing the window moved from closed position.

Fig. 4 is an enlarged view similar to Fig. 2.

Fig. 5 is a perspective view of a portion of the weatherstrip.

Fig. 6 is a diagrammatic view of the weatherstrip showing in dotted lines the position assumed thereby when in released position.

In terms of broad inclusion, the weatherstrip of the present invention comprises a strip of suitable resilient material secured to the casement of a hinged closure with a portion of the strip deflected from the secured part to resiliently engage the inside corner

of the window. A flange is provided upon the other side of the strip to engage the outer face of the window, and a plurality of weep-holes are provided adjacent the base of the flange to permit the escape of any water which may become entrapped therebehind.

In greater detail, the preferred embodiment of the weatherstrip of the present invention is shown positioned upon the lower rail or sill 6 of the casement 7 within which a casement window 8 is hung by hinges 9. The weatherstrip which is indicated in its entirety by the numeral 11, is preferably formed of an elongated strip of resilient, non-corrosive metal such as brass or bronze. It is bent throughout its length in a tight, reverse bend 12 to provide a double upright flange 13 extending longitudinally of the weatherstrip 11. One of the sides 14 of the flange 13 extends laterally from the bottom of the flange to provide a fastening edge 16, the angle between the fastening edge 16 and the upright flange being preferably less than 90° so that when the weatherstrip is positioned upon the conventional sloping sill 17, the flange 13 will extend substantially vertically. A plurality of nails 21 or other suitable fastening means may be driven through the strip 11 to rigidly secure it to the sill 17.

The body portion 22 of the weatherstrip 11, extends from the bottom of the other side 23 of the flange 13 under the fastening edge 16, and is inclined upwards as at 24 from below the fastening edge 16 to engage the inner, lower corner 27 of the window 8 when the latter is in closed position. The inner edge 23 of the weatherstrip 11 is curled downwards to present an inclined surface 29 against which the outer corner 31 of the window 8 may impinge as the window 8 is being closed, to spring the inclined portion 24 downwards from its releasing position, which is indicated in dotted lines in Fig. 6, and permit the window to pass to fully closed position. It is to be understood that the natural resiliency of the material of which the weatherstrip is composed, is such that when the window 8 is in fully closed position, the inclined portion 24 will press tightly against the inner lower corner 27 of the window, to establish a tight seal between the window and the sill 17, as shown in full lines in Fig. 6.

The proportionate size and arrangement of the parts is such that the outer face 32 of the

window strikes the flange 13 just after the inner lower corner 27 has passed the curled edge 28 as the window is closing. Thus a double seal is provided against the passage of water 5 or wind between the sill 17 and the window 8.

A plurality of weep-holes 33 are provided adjacent the base of the flange 13 to permit the escape of any water which might leak into the space 34 between the bottom of the 10 window 8 and the weatherstrip 11. The upward inclination of the body portion 22 from the flange 31 will preclude the possibility of the leakage of such water to the inside of the casement 7 either by gravity or by capillary 15 attraction. Thus it may be seen that I have provided an improved type of weatherstrip which is especially adapted to provide a weather tight seal between the bottom of a casement window and the sill. The weatherstrip is of such width that it extends clear 20 across the bottom of the window from the outer face to a position slightly beyond the inner face thereof, the vertical flange engaging the outer face and the angularly inclined body portion engaging the lower inner corner. It may be readily appreciated that a 25 weatherstrip of such characteristics is not only capable of efficiently sealing the space between the window and the sill, but is also capable of being very inexpensively manufactured and very easily installed.

The weatherstrip is preferably formed of relatively thin material, such as 32-gauge 30 spring metal. When constructed of such thin material, it is unnecessary to provide the weatherstrip with holes for the reception of the fastening means 21, as the fastening means may be driven right through the material.

40 It is also unnecessary to bend the body portion 22 to provide the inclined portion 24. Instead, the weatherstrip may be secured to the sill 17 while flat, and then a blunt instrument run across the body portion 22, using the fastening edge 16 as a straightedge. By pressing the blunt instrument down hard 45 upon the body portion, the latter may be scored and bent upwards to provide the inclined portion 24.

50 Various changes in the details of construction may be made without departing from the spirit and scope of the invention as defined by the appended claims.

I claim:

55 1. A weatherstrip for establishing a seal between a hingedly mounted closure and its casing, and comprising a resilient strip secured adjacent one edge to said casing, said strip being deflected from adjacent its attached edge toward said closure in the direction of opening thereof, to be engaged by an inside corner of the closure when closed, and a flange extending from said strip to engage the outside face of the closure when closed.

2. A weatherstrip for establishing a seal 70 between a hingedly mounted closure and its casing, and comprising a resilient strip secured adjacent one edge to said casing, said strip being deflected from adjacent its attached edge toward said closure in the direction of opening thereof, to be engaged by an inside corner of the closure when closed, and a flange extending from said strip to engage the outside face 75 of the closure when closed.

3. A weatherstrip for establishing a seal 80 between a hingedly mounted closure and its casing, and comprising a resilient strip secured adjacent one edge to said casing, said strip being deflected from adjacent its attached edge toward said closure in the direction of opening thereof, to be engaged by an inside corner of the closure when closed, and the unattached edge of the strip being curled 85 toward that portion of the casement to which the strip is attached, and a flange extending from said strip to engage the outside face of the closure when closed.

4. A weatherstrip for establishing a seal 90 between a hingedly mounted closure and its casing, and comprising a resilient strip secured adjacent one edge to said casing, said strip being deflected from adjacent its attached edge toward said closure in the direction of opening thereof, to be engaged by 95 and extend beyond an inside corner of the closure when closed, and the unattached edge of the strip being curled toward that portion of the casement to which the strip is attached, and a flange extending from said strip to engage the outside face of the closure when closed.

5. A weatherstrip for establishing a seal 105 between a hingedly mounted closure and its 100 casing, and comprising a resilient strip secured adjacent one edge to said casing, said strip being deflected from adjacent its attached edge toward said closure in the direction of opening thereof, to be engaged by 110 an inside corner of the closure when closed, and a flange extending from said strip to engage the outside face of the closure when closed, said strip being provided with a plurality of weep-holes adjacent the base of said 115 flange.

6. A weatherstrip for establishing a seal 120 between a hingedly mounted closure and its casing, and comprising a resilient strip secured adjacent one edge to the bottom of said casement, said strip being deflected upward from adjacent its attached edge in the direction of opening of the closure to be engaged by an inside corner thereof when closed, and a flange extending upward from 125 said strip to engage the outer face of the closure when closed.

7. A weatherstrip for establishing a seal 130 between a hingedly mounted closure and its casing, and comprising a resilient strip se-

- cured adjacent one edge to the bottom of said casement, said strip being deflected upward from adjacent its attached edge in the direction of opening of the closure to be engaged by an inside corner thereof and to extend beyond and above said corner when the closure is closed, and a flange extending upward from said strip to engage the outer face of the closure when closed.
- 10 8. A weatherstrip for establishing a seal between a hingedly mounted closure and its casing, and comprising a resilient strip secured adjacent one edge to the bottom of said casement, said strip being deflected upward from adjacent its attached edge in the direction of opening of the closure to be engaged by an inside corner thereof and to extend beyond and above said corner when the closure is closed and the unattached edge of the strip being curled to extend downwards, and a flange extending upward from said strip to engage the outer face of the closure when closed.
- 15 9. A weatherstrip comprising a resilient strip bent to provide an upright flange extending longitudinally of the strip, a fastening edge extending laterally from the bottom of the flange, and a body portion inclining upwards to the same side of the weatherstrip from below the flange, the upper edge of said body portion being curled.
- 10 10. A weatherstrip for establishing a seal between a hingedly mounted closure and its casing, and comprising a resilient strip secured adjacent one edge to said casing, said strip being deflected from adjacent its attached edge toward said closure in the direction of opening thereof to be engaged by an inside corner of the closure when closed.

In testimony whereof I have signed my name to this specification.

CLARENCE R. DE LAUBENFELS.
